Primary Examiner — Kelley Donnelly(74) *Attorney, Agent, or Firm* — Keating & Bennett, LLP(57) **CLAIM**

The ornamental design for a meat crate, as shown and described.

DESCRIPTION

FIG. 1 is a top perspective view of a meat crate according to my new design in an unfolded state;

FIG. 2 is a right side view thereof in an unfolded state;

FIG. 3 is a top view thereof in an unfolded state;

FIG. 4 is a top view thereof in a folded state;

FIG. 5 is a front view thereof in an unfolded state; and,

FIG. 6 is a bottom view thereof in an unfolded state.

The broken lines are for the purpose of illustrating the environment of the design only and form no part of the claimed design.
